UNITED STATES PATENT OFFICE.

GIDEON PILLOW BROWN, OF LAKE BLUFF, ILLINOIS, ASSIGNOR TO BLANCHE WRIGHT BROWN, OF LAKE BLUFF, ILLINOIS.

HAND-HOLE SCRAPER.

1,308,221.

Specification of Letters Patent.

Patented July 1, 1919.

Application filed October 31, 1913, Serial No. 798,423. Renewed November 8, 1918. Serial No. 261,715.

To all whom it may concern:

Be it known that I, GIDEON PILLOW BROWN, a citizen of the United States of America, and resident of Lake Bluff, Lake county, Illinois, have invented a certain new and useful Improvement in Hand-Hole Scrapers, of which the following is a specification.

My invention relates to hand hole scrapers in general, but more particularly to those for use in connection with boilers having oval hand holes.

The object of my invention is to provide a hand hole scraper that can be rotated continuously in one direction on the edges of an oval or other non-circular hand hole.

It is also an object to provide a hand hole scraper having means for holding it in place during the operation thereof.

Another object is to provide certain details and features of improvement tending to increase the general efficiency of a hand hole scraper of this particular character.

To these and other useful ends my invention consists in matters hereinafter set forth and claimed.

In the accompanying drawings:

Figure 1 is a side elevation of a hand hole scraper embodying the principles of my invention.

Fig. 2 is an end elevation of said scraper, showing the same at work on the edges of the oval hand hole.

Fig. 3 is an outside elevation of the said scraper.

Fig. 4 is a vertical section on line 4—4 in Fig. 1.

Fig. 5 is a vertical section on line 5—5 in Fig. 1.

Fig. 6 is a vertical section on line 6—6 in Fig. 2.

Fig. 7 is a perspective of the cam plate which operates the wedges for engaging the outer surfaces of the boiler, around the hole, to crowd the cutting knives hard against the inner edge portions of the said hole.

Fig. 8 is a perspective of an intermediate plate for holding the blades in position.

As thus illustrated, my invention comprises a body A having a cam groove *a* for the rollers *a*¹ on the radially disposed knives B. These knives slide in guides C removably secured to the inner end of the shaft D, by a pin *c* and are of any suitable number. The body or head A is made oval to fit the

oval hand hole in the boiler X, and when the shaft is rotated by the handle *d*, the knives B move out and in, as the rollers *a*¹ travel in the oval cam groove *a*. Thus the knives are compelled to follow the oval edge 60 of the hand hole, while the instrument is rotated continuously in one direction. The face *b* of each knife is preferably grooved or corrugated to more effectually cut the substances away from the seat around the hand 65 hole. The holding fingers or wedges E are arranged for radial movement, and are held in place on the body A by means of an oval plate *e*, which latter is secured in place by screws *e*¹ inserted in the body A of the 70 scraper. A rotary cam plate F is disposed between said body A and the plate *e*, in a recess *a*² in the body A and is provided with curved or tangential cam grooves *f*. The rollers *e*¹ on the fingers E engage in the said 75 grooves *f*, and said plate F has a hub or sleeve *f*¹ extending outward and over the shaft D. The end of this sleeve *f*¹ has an arm *f*² provided with means *f*³ for engaging the curved rack *f*⁴ on the plate *e*. By moving said arm *f*² the cam plate F is rotated, and this causes the fingers E to move outward. Said fingers have beveled end surfaces *e*² that slide over on to the edges of the hand hole, and in this way these fingers act 80 like wedges to pull the scraper outward, causing the knives B to bear hard against the inner edges of the hole. The means *f*³, by engagement with the rack *f*⁴, serves to hold the arm *f*² in adjusted position, and 90 thus the fingers can be tightened on the edges of the hole, from time to time, as the work progresses. In this way the operator does not have to pull on the scraper, but simply turns the handle *d*, and adjusts the arm *f*² to 95 keep the knives in close contact with the inner edges of the hole.

The mechanism of the scraper can, of course, be modified or changed to adapt it for use with holes of different shapes and sizes.

If desired, the blades B can be separated from the plate A by an intermediate wearing plate G having an opening *g* for the shaft D and slots *g*¹ for the axles *g*² of the 105 rollers *a*¹. The said plate can be of metal, and may be provided with a thick back portion *g*³, if desired, or may be formed in any other suitable manner. This plate G can be secured in place in various ways, as for ex- 110

ample by fastening it to the guides C. The plate A has a seat g^4 for the plate G, whereby the latter is flush with the former. As shown the portion g^3 is much thicker than 5 the plate G and in the form of a separate plate.

I do not limit myself to the exact construction shown and described.

What I claim as my invention is:

- 10 1. A scraper for cleaning the edges of oval or other non-circular hand holes, comprising knives for engaging the edges of the hole, means for rotating the knives about an axis substantially central of said hole, and a support for said means, serving to keep the scraper in proper position, held against movement by engagement with the structure around said hole, and means for causing said knives to move toward and away from 15 the said axis to follow the contour of said hole.
- 20 2. A scraper for cleaning the edges of oval or other non-circular hand holes, comprising knives for engaging the edges of the hole, 25 means for rotating the knives about an axis substantially central of said hole, and a support for said means, serving to keep the scraper in proper position, held against movement by engagement with the structure 30 around said hole, said support having a cam groove of the same shape as said hole, and said knives having means for engaging said groove, whereby the knives follow the contour of said hole.
- 35 3. A scraper for cleaning the edges of oval or other non-circular hand holes, comprising knives for engaging the edges of the hole, means for rotating the knives about an axis substantially central of said hole, and a support 40 for said means serving to keep the scraper in proper position, held against movement by engagement with the structure around said hole, together with adjustable means for forcing the scraper outward to 45 keep the knives in working engagement with the edges of the hole.
- 50 4. A scraper for cleaning the edges of oval or other non-circular hand holes, comprising knives for engaging the edges of the hole, means for rotating the knives about an axis substantially central of said hole, and a support for said means, serving to keep the scraper in proper position, held against movement by engagement with the structure 55 around said hole, together with movable fingers provided with beveled surfaces for engaging the outer edges of the hole, and means for operating said fingers, serving to keep the knives in working engagement with 60 the inner edges of the hole.
- 60 5. A hand hole scraper having knives, means for rotating the knives, means for causing the knives to move bodily toward and away from the axis of rotation, in the 65 common plane of said knives, operated by

the said rotation, serving to cause the knives to follow the shape of the hole, and means acting in conjunction with said hole to support the scraper in operating position, having provisions operating by rotation about 70 said axis to release said last mentioned means from the hole.

6. A hand hole scraper provided with knives, means for rotating the scraper, provisions whereby the said knives move bodily 75 toward and away from the axis of rotation, in the common plane of said knives, thereby enabling the knives to follow the shape of the hole, and means acting in conjunction with said hole to support the scraper in operating position, having provisions operating by rotation about said axis to release said 80 last mentioned means from the hole.

7. A hand hole scraper having knives for operating on the inner edges of the hole, and 85 readily adjustable means for engaging the structure around the hole, on the outside thereof, serving to pull the scraper outward, thereby keeping the knives in working engagement with the edges of the hole, and a 90 rotary element for causing said means to engage and disengage the structure.

8. A hand hole scraper having knives for operating on the inner edges of the hole, and 95 radially adjustable means for engaging the structure around the hole, on the outside thereof, serving to pull the scraper outward, thereby keeping the knives in working engagement with the edges of the hole, said means including a plurality of radial fingers, 100 a rotary cam plate, means for engaging said cam plate, carried on said fingers, and means for rotating said cam plate to cause said fingers to engage the structure.

9. A scraper for cleaning an object having a non-circular edge or rim, comprising a rotary head, a plurality of cutters disposed in position for scraping said object, movably mounted in said head to follow the contour of said edge or rim, a stationary 105 cam for controlling the operation of said cutters, a handle for rotating said head, and means for engaging said edge or rim to prevent relative rotation between said object and said cam during the operation of the 110 scraper, said cam and means being provided with a support in the form of a stationary head, and said object and stationary head being disposed one within the other during 115 operation of the scraper.

10. A scraper for cleaning an object having a non-circular edge or rim, comprising a rotary head, a plurality of cutters disposed in position for scraping said object, movably mounted in said head to follow the contour of said edge or rim, a stationary cam for controlling the operation of said cutters, a handle for rotating said head, and means for engaging said edge or rim 125 to prevent relative rotation between said 120 object and said cam during the operation of the scraper.

object and said cam during the operation of the scraper, said cutters working at one side of said object when the scraper is in use, and devices for bearing against the other 5 side of said object to draw said cutters into working contact with said edge or rim, said cutters and devices being spaced apart to receive the edge portion of said object.

11. A scraper for cleaning an object having a non-circular edge or rim, comprising 10 a rotary head, a plurality of cutters disposed in position for scraping said object, movably mounted in said head to follow the contour of said edge or rim, a stationary 15 cam for controlling the operation of said cutters, a handle for rotating said head, and means for engaging said edge or rim to prevent 20 relative rotation between said object and said cam during the operation of the scraper, said cam and means being provided with a support in the form of a stationary 25 head having said edge or rim extending around the outside thereof when the scraper is in use, and adjustable devices mounted on said stationary head and engaging said object to force said cutters into working contact with said edge or rim.

12. A scraper for cleaning an object having a non-circular edge or rim, comprising 30 a rotary head, a plurality of cutters disposed in position for scraping said object, movably mounted in said head to follow the contour of said edge or rim, a stationary cam for controlling the operation of said cutters, 35 a handle for rotating said head, and means for engaging said edge or rim to prevent relative rotation between said object and said cam during the operation of the scraper, said cam being in the form of a plate having 40 a groove, and said cutters being arranged to slide between said plate and head, each cutter having means for engaging said groove.

13. A scraper for cleaning an object having a non-circular edge or rim, comprising 45 a rotary head, a plurality of cutters disposed in position for scraping said object, movably mounted in said head to follow the contour of said edge or rim, a stationary cam for controlling the operation of said cutters, 50 a handle for rotating said head, and means for engaging said edge or rim to prevent relative rotation between said object and said cam during the operation of the scraper, 55 said cam being in the form of a plate having a groove, and said cutters being arranged to slide between said plate and head, each cutter having means for engaging said groove, and a wearing plate interposed between said cam and cutters, 60 said wearing plate having slots for permitting said cutters to slide toward and away from the axis of rotation.

14. A scraper for cleaning an object having a non-circular edge or rim, comprising 65 a rotary head, a plurality of cutters disposed in position for scraping said object, movably mounted in said head to follow the contour of said edge or rim, a stationary cam for controlling the operation of said cutters, 70 a handle for rotating said head, and means for engaging said edge or rim to prevent relative rotation between said object and said cam during the operation of the scraper, 75 a plurality of fingers for drawing said head forward to keep said cutters in working contact with said object, a rotary plate having cam slots for moving said fingers into and out of engagement with said object, and means for rotating said plate.

Signed by me at Chicago, Illinois, this 27th day of October, 1913.

GIDEON PILLOW BROWN.
